United States Patent Office.

THOMAS BOND, OF EAST BROOKFIELD, MASSACHUSETTS, ASSIGNOR TO DANIEL J. CLARK, W. F. DOGGETT, AND S. M. BURR, OF COLUMBUS, OHIO.

Letters Patent No. 99,284, dated February 1, 1870.

IMPROVED TRUNK.

The Schedule referred to in these Letters Patent and making part of the same

To all whom it may concern:

Be it known that I, THOMAS BOND, of East Brookfield, in the county of Worcester, and State of Massachusetts, have invented a new and improved Trunk; and I do hereby declare that the following is a full, clear, and exact description thereof, which will enable those skilled in the art to make and use the same, reference being had to the accompanying drawings, forming part of this specification, in which—

Figure 1 is a front view of my invention with the lid open.

Figure 2, a front view of the same in a closed state.

Similar letters of reference indicate corresponding parts.

This invention consists in constructing a trunk, with semicircular or rounded corners or ends, bent in such form, out of one or more pieces of wood, whereby a trunk of greater strength than usual is obtained.

The drawings represent a trunk constructed according to my invention, with its main part and lid formed each out of two pieces of wood, A A A' A'.

These pieces may be bent in any suitable way by the aid of a machine or otherwise, and they may be secured at their ends by a mortise-and-tenon joint, a, or by dovetailing, halving, or by metal dowels, the joints being at the front and rear of the trunk.

The bottom B of the trunk, I design to fit into the lower edge of the main part by a rebate, as shown by the dotted lines b, and the top C, I design to fit into the lid in a similar manner, as shown in the dotted lines c. This will add greatly to the strength of the trunk, preventing its sides and the top and bottom from being pressed in.

By this mode of construction, a trunk is rendered far more durable than usual. The sharp or angular corners of the ordinary trunks are very liable to be broken, and they generally fail at those points.

While disclaiming novelty in the general principle of making boxes of bent wood,

I claim as my invention, and desire to secure by Letters Patent—

The combination and arrangement of the rebated bottom B b, rebated top C c, bent body-pieces A A, and bent rims A' A', the whole constructed and secured as herein specified, and constituting an improved manufacture of travelling-trunks.

THOMAS BOND.
